UNITED STATES PATENT OFFICE.

LOUIS C. GALLI, OF NEW YORK, N. Y.

TEMPERATURE REGULATOR FOR INTERNAL-COMBUSTION ENGINES.

1,409,698.

Specification of Letters Patent. Patented Mar. 14, 1922.

Application filed October 22, 1917. Serial No. 197,991.

To all whom it may concern:

Be it known that I, LOUIS C. GALLI, a citizen of Switzerland, and a resident of the city of New York, in the borough of Manhattan, county and State of New York, have invented certain new and useful Improvements in Temperature Regulators for Internal-Combustion Engines, of which the following is a specification.

10 This invention relates to means, herein illustrated as shutters, for regulating the temperature of internal combustion engines, and means for automatically actuating the same.

15 It is an improvement on the invention of my application Serial No. 156,359 filed March 21, 1917 wherein the power for operating the shutters is specifically illustrated as derived from the oil-circulating means.

20 In this invention the power for operating the shutters is derived from the partial vacuum on the intake side of the engine, and the object of this invention is the provision of means such as above indicated 25 which shall be so actuated that the shutters or other means will remain closed at all times while the engine is not running; and also while the engine is running until the desired temperature within the hood is 30 reached when the shutters or other means are automatically opened and remain open for all temperatures thereabove but close automatically when the temperature drops below that point.

35 It will, of course, be understood that, while a vacuum is stated as the means of operation, the power actually comes from the pressure of the atmosphere. However, without the vacuum, atmospheric pressure 40 would manifestly be inoperative, and therefore in this sense the vacuum may be regarded as the operating means.

In the accompanying sheet of drawings which forms a part of this application—

45 Figure 1 is a side elevation, partly broken away, of the form of this invention chosen for illustrative purposes, with an automobile radiator and engine conventionally shown; and

50 Fig. 2 is a partial vertical section of certain of the operative parts of Fig. 1.

The shutters 44 herein illustrated are arranged in a bank for simultaneous operation, and are so constructed that when 55 closed they completely cover the front of the radiator 5. They are suitably mounted

in proximity to the radiator, each shutter being preferably pivotally mounted along its central longitudinal line, suitable mounting such as a frame 6 being provided where 60 necessary.

The connecting of the shutters is accomplished by a bar 7 which has horizontally projecting ears 8 8, with which oppositely projecting ears 9 9 in the rear upper part 65 of each shutter are hinge connected. These parts are consequently hidden from view when the shutters are closed, as is illustrated in Fig. 2.

On the interior of the radiator and in a 70 convenient place is suitably mounted an actuating device or motor here illustrated as comprising a chamber 10 backed with a diaphragm of flexible material 11. To the diaphragm is attached a rod 12 which extends 75 through the radiator and is suitably connected with the shutters. The connection illustrated comprises a link 13 pivotally connected with an angle arm 14 which is rigidly connected with one of the shutters. The 80 diaphragm is illustrated as being extended by a spring 15 in a direction to close the shutters.

The chamber is connected with the intake of the engine, as by a small tube 16 which 85 connects with the inlet pipe 17 between the carburetor 18 and the engine. When the engine is running there is a drop of pressure or partial vacuum in the inlet pipe and by reason of the connection of the chamber 90 10 through the small tube there will be substantially the same amount of vacuum in the chamber, provided there is no leak into the chamber; and under these conditions the diaphragm will be moved forward, 95 pushing the rod outwardly and opening the shutters. As here shown the rod and the diaphragm are connected by means of a block 19 into which the rod is screwed and to which the diaphragm is attached by 100 means of a clamping nut 20.

A normally open leak into the chamber is provided through the block 19 as by a central hole 21 and two branch holes 22 22, the branch holes being provided because one 105 end of the central hole as here illustrated is closed by the rod. A yoke is clamped between the block and its nut and is supported therefrom. It comprises a bent strap 23 and a perforated flanged disk 29, to the 110 flange of which the ends of the strap are attached. The yoke supports a thermostat

shown as consisting of two hollow disks 24 24 the first of which is adjustably supported on a screw 25, which extends through the perforated disk, and the second of 5 which is supported from the first. The second disk carries a needle 26 which enters the central leak hole, thereby forming a needle valve which is closed when the hollow disks are distended by the heat. Through the 10 adjusting screw the thermostat can be set to close the leak at any desired temperature of the engine chamber and then locked by a nut 27.

A perforated guard 28, suitably attached 15 to the chamber, is provided to protect the thermostat from mechanical injury, and may also serve as a guiding support for the yoke. The perforations in the guard and in the disk-cap of the yoke permit circulation of air from the engine chamber.

The operation is as follows:

When the engine is set at rest or the air in the engine chamber is below the temperature at which the shutters are to be open, 25 the flexible diaphragm is pushed back by the spring 15, the connecting rod 12 is retracted, and the shutters are drawn together as shown in Fig. 1. On starting the engine a drop in pressure below atmospheric will 30 be created in the intake pipe and maintained while the engine continues to run, and air will be drawn from the chamber of the motor. However, until there is a rise in temperature, there will be no material drop in 35 pressure in the chamber owing to the leak through the needle valve, and the motor will not operate to open the shutters. But when the temperature is reached for which the apparatus is adjusted the needle-valve closes 40 cutting off the leak, and the pressure in the chamber drops to substantially the vacuum of the intake pipe of the engine. The diaphragm is then pressed forward by the atmospheric pressure on the outer side, moving 45 the connecting rod forwardly and opening the shutters. Upon the stoppage of the engine the vacuum in the motor chamber is immediately broken through the tube 16, thereby balancing pressures on the two sides 50 of the diaphragm and permitting the spring 15 to draw the shutters together, regardless of whether or not the temperature has fallen sufficiently to open the needle-valve. The air which finds its way, in the construction 55 illustrated, into the intake pipe of the engine through the shutter-operating motor is inconsequential in its influence on the proportions of the mixture supplied to the engine.

60 The drawings herein indicate one form of the invention only in order that the invention may be readily comprehended, but it is to be understood that the invention is by no means confined to the specific form herein 65 illustrated; and the foregoing detailed de-

scription has been given for clearness of understanding and no undue limitation should be deduced therefrom, but the appended claims should be construed as broadly as permissible in view of the prior 70 art.

What I claim as new and desire to secure by Letters Patents of the United States is:

1. In a capacity regulating means for the cooling system of an internal combustion 75 engine, the combination of a shield, a motor for operating the shield comprising a fixed member and a movable member, means for controlling the motor dependent in their operation upon a difference of air pressures, 80 and means carried in fixed relation with the movable member of the motor for determining said difference of air pressures.

2. In a capacity regulating means for the cooling system of an internal combustion 85 engine, the combination of a shield, a motor for operating the shield comprising a fixed member and a movable member, means for controlling the motor dependent in their operation upon a difference of air pressures, 90 and thermostatic means carried in fixed relation with the movable member of the motor for determining said difference of air pressures.

3. In a capacity regulating means for the 95 cooling system of an internal combustion engine, the combination of a shield, a motor for operating the shield comprising a fixed member and a movable member, means for controlling the motor dependent in their 100 operation upon a difference of air pressures, thermostatic means carried in fixed relation with the movable member of the motor for determining said difference of air pressures, and means independent of the thermostatic 105 means for nullifying the effect of the thermostatic means.

4. The combination of an internal combustion engine, a cooling system therefor, means for varying the capacity of the cooling system, a chamber connected with the intake of the engine, a flexible diaphragm closing the mouth of the chamber and connected with the capacity varying means so as to increase the cooling capacity when 110 drawn into the chamber by a vacuum therein, a leak through the diaphragm for preventing the formation of a vacuum in the chamber, a thermostat mounted on the diaphragm, and means operated by the thermostat for closing the leak, substantially as described.

5. The combination of an internal combustion engine, a cooling system therefor, means for varying the capacity of the cooling system, a chamber connected with the intake of the engine, a flexible diaphragm closing the mouth of the chamber and connected with the capacity varying means so as to increase the cooling capacity when 115 120 125 130

drawn into the chamber by a vacuum therein, a valve for preventing the formation of a vacuum in the chamber, and a thermostat carried in fixed relation with the diaphragm 5 for actuating the valve.

6. The combination of an internal combustion engine, a cooling system therefor including a radiator, means for controlling the cooling capacity of the radiator, actuating means embodying a movable member directly responsive to suction produced in the engine cylinders for operating the controlling means, and thermostatic means carried in fixed relation with said movable 10 member for governing the operation of the actuating means.

7. A capacity regulating means for the

cooling system of an internal combustion engine comprising a motor embracing a fixed member and a movable member, means 20 for controlling the motor dependent in its operation upon a difference in fluid pressures on opposite sides of the movable member, one of the pressures being produced by the engine, and thermostatically controlled means carried in fixed relation with the movable member for determining said difference of pressures.

Signed at New York, N. Y. this 18th day of October, 1917.

LOUIS C. GALLI.
